Primary Examiner — Cynthia R Underwood(74) *Attorney, Agent, or Firm* — Lee & Hayes, P.C.(57) **CLAIM**

The ornamental design for a wall cleat, as shown and described.

DESCRIPTION

FIG. 1 is a top, front, right-side perspective view of a wall cleat showing the new design;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a top, front, right-side perspective view thereof; and,

FIG. 10 is a right-side view thereof.

The stippled shading shown in FIGS. 2 and 4 represents a second surface texture (e.g., an adhesive pad) of the wall cleat.

The dashed broken lines in FIGS. 9 and 10 depict environment of the wall cleat that forms no part of the claimed design. The dot-dashed broken lines represent boundaries of the claimed design and form no part of the claimed design.
